UNITED STATES PATENT OFFICE.

PERLEY R. GLASS, OF BROOKLINE, AND HENRY G. HALLORAN, OF DORCHESTER, MASSACHUSETTS, ASSIGNEES TO P. R. GLASS COMPANY, OF BOSTON, MASSACHUSETTS, A CORPORATION OF MASSACHUSETTS.

METHOD OF FINISHING THE EDGES OF LEATHER.

1,181,758.

Specification of Letters Patent.

Patented May 2, 1916.

Application filed June 23, 1913. Serial No. 776,227.

To all whom it may concern:

Be it known that we, PERLEY R. GLASS and HENRY G. HALLORAN, citizens of the United States, residing at Brookline, county 5 of Norfolk, and Dorchester, county of Suffolk, State of Massachusetts, respectively, have invented an Improvement in Methods of Finishing the Edges of Leather, of which the following description, in connection with 10 the accompanying drawing, is a specification, like characters on the drawing representing like parts.

This invention relates to methods of finishing the edges of leather, particularly such 15 as are used in shoe uppers so as to produce smoothly rounded edges in the place of the raw edges formed by cutting the leather, so that the leather may be used in places in the 20 finished article where the edges of the leather are exposed.

The objects of the invention are primarily to save the time, labor and expense of cementing and folding back or otherwise securing the edges of the leather as is 25 commonly done in the art, and also to save the leather which otherwise would be wasted in the skiving and folding.

Generally speaking the invention consists 30 in skiving the edges of the leather and treating the skived portion with a plastic material which has the property of contracting when drying, thus causing the thin edge of the leather to be curled under in such a manner as to form a smooth and finished 35 edge.

In performing the process constituting this invention the leather may be skived on any suitable skiving machine and the plastic material applied to the skived edge either by 40 hand or by suitable machinery. In order further, to turn in the finished edge, we deem it preferable to treat the edge with a smoothing or burnishing tool.

The manner in which the leather is treated 45 in accordance with our invention, is fully disclosed in the following description and the accompanying drawings in which—

Figure 1 is a side elevation, partly in section, of a burnishing machine of an ordinary 50 type. Fig. 2 is a plan view of a piece of skived leather. Fig. 3 is a sectional view of the same. Fig. 4 is a plan view of a piece of leather in which the skived edge has been treated with the contractive plastic mate-

rial. Fig. 5 is a sectional view of the same. Fig. 6 is a sectional view of a piece of treated leather sewed to a plain piece of leather and illustrating the manner in which the rounded finished edge appears in use.

The burnishing machine shown in Fig. 60 1 comprises a bedplate 1 to which is attached a bearing 2 carrying a shaft 3 which supports a feeding wheel 4. Arising from the bedplate 1 is an arm or frame 5 (partly broken away) having a bifurcated end provided with bearings 6 and 7 which support the shaft 8 of a burnishing or other tool 9. The ends of the bifurcated arm 5 provide bearings 10 and 11 for the shank 12 of a presser foot 13, the presser foot being maintained in position to coöperate with the feeding wheel by a helical spring 14.

The shaft 3 is driven in any suitable manner, and the shaft 8 of the burnishing wheel is driven by a belt 15 passing around a pulley 16 and a suitable power transmitting mechanism. The peripheral speed of the tool 9 may be the same as that of the feeding wheel in which case the tool merely serves to smooth and condense the edge of the 75 leather, or it may be driven at a speed considerably in excess of that of the feeding wheel, in which case the tool will have a burnishing action upon the edge of the leather.

Heretofore in finishing the edges of leather it has been necessary to skive at a very acute angle to permit the folding over of the grain side of the leather and the securing of the folded portion to the body of the leather by stitching, cementing or otherwise. By this invention the edge of the leather may be skived at such an angle as to waste very little leather. This angle need only be such as to enable the edge to curl 90 or be turned in to present the grain or finished side or face of the leather at the edge. An angle of but 45° has been found satisfactory.

The skived edge of the leather is treated 100 with a plastic material having the properties of firmly adhering to the surface of the leather and of contracting when drying sufficiently to cause the thin edge of the leather to curl toward the thicker portion and thus 105 produce a rounded finished edge. It has been found in practice that a contractive plastic material of such character may be

produced by treating nitrated or acetelated cellulose with fusel oil or amyl acetate and thereafter dissolving the same in a volatile hydrocarbon such as ether, acetone, alcohol or amyl alcohol or preferably in a mixture of acetone and alcohol. Celluloid, such as scrap celluloid, may also be used in solution with volatile hydrocarbons, including those above mentioned, particularly good results having been obtained from a solution of celluloid in a mixture of acetone and alcohol in the proportion of 16 ounces of celluloid to one gallon each of acetone and alcohol. A small amount of resinous gum such as copal or East India gum, may be added to the solution, if desired, for the purpose of giving body to the plastic composition and of increasing its flexibility when dried. A suitable dye may also be added to the solution when the same is to be used upon tan, black or other colored leather in order that the leather may not show the effect of treatment.

While the plastic compositions above described have been found to be practical and efficient for the purpose set forth, it is to be understood, however, that our invention is not limited to these products, but includes any plastic material having the properties of being leather adherent and contractive upon drying, the particular compositions to which reference has been made being illustrative but not restrictive.

In finishing the edge by our process it is not necessary that the edge be wholly curled under as illustrated in the drawing. In many cases it will be found sufficient if the edge is slightly curled inasmuch as the plastic composition is of a water repellent character and adapted permanently to retain the edge of the leather in its rounded form.

While the treatment of the skived edge of the leather with a contractive plastic composition as above described is ordinarily sufficient to produce a perfect finished edge, it is found that some classes of leather are less susceptible to the contractive action of the plastic composition, and that in others there is a lack of uniformity in the character or a variation in porosity of different portions of the same piece. In such cases the alinement and the uniform curvature of the finished edge may be insured by applying pressure to the same by means of a die or preferably by the progressive application of pressure by an edge forming machine such as that above described, (or by passing the edge of the leather through an edge rounding machine). So far as the securing of the proper alinement and curvature of the edge is concerned it is not necessary that the tool or wheel 9 of the machine described shall move faster than the feed of the leather edge. But it is frequently desirable to

finish the edge by burnishing and by the machine described this burnishing operation is thus performed simultaneously, and by the same machine which assures the required edge alinement and curvature.

The treated edge may be subjected to such pressure either before the plastic material is completely dried or thereafter, since the plastic composition above described is of such character as permanently to adapt itself to the form given it by the pressure applying device.

Having fully described our invention, what we claim as new and desire to secure by Letters Patent is:

1. The process of producing a rounded, smooth and finished edge upon leather, which consists in slightly skiving the edge, and coating the skived portion with a solution of contractive plastic material, whereby the skived portion of the leather is caused to contract and curl.

2. The process of producing a rounded, smooth and finished edge upon leather, which consists in slightly skiving the edge from the flesh side, and coating the skived portion with a solution of contractive plastic material, whereby the marginal portion of the grain side of the leather is caused to curl toward the flesh side.

3. The process of producing a rounded, smooth and finished edge upon leather, which consists in slightly skiving the edge, and coating the skived portion with a preparation of water repellent contractive, plastic material, whereby the marginal portion of one side of the leather is caused to curl toward the other side.

4. The process of producing a rounded, smooth and finished edge upon leather, which consists in slightly skiving the edge, coating the skived portion with a solution of contractive plastic material, whereby the marginal portion of one side of the leather is caused to curl toward the other side, and finally applying suitable pressure to the edge to insure its alinement and uniform degree of curvature.

5. The process of producing a rounded, smooth and finished edge upon leather, which consists in slightly skiving the edge from the flesh side, coating the skived portion with a solution of contractive plastic material, whereby the marginal portion of the grain side of the leather is caused to curl toward the flesh side, applying suitable pressure to the edge to insure its alinement and uniform curvature, and simultaneously burnishing the curled portion to complete the finished edge.

6. The process of producing a rounded, smooth and finished edge upon leather, which consists in slightly skiving the edge, and coating the skived portion with a cellulose solution which has the property of con-

tracting when drying, whereby the marginal portion of the grain side of the leather is caused to curl toward the flesh side.

7. The process of producing a rounded, smooth and finished edge upon leather, which consists in slightly skiving the edge, and coating the skived portion with a preparation of cellulose dissolved in volatile hydrocarbon, whereby the skived portion is caused to contract when the coating dries to cause the treated portion to curl.

8. The process of producing a rounded, smooth and finished edge upon leather, which consists in slightly skiving the edge from the flesh side and coating the skived portion with a preparation of cellulose dissolved in a mixture of volatile hydro-carbons whereby the treated portion is caused to contract upon drying, and the grain side of the leather to curl toward the flesh side.

9. The process of producing a rounded, smooth and finished edge upon leather, which consists in slightly skiving the edge from the flesh side and coating the skived portion with a preparation of cellulose dissolved in volatile hydro-carbon, whereby the treated portion is caused to contract upon drying, and the grain side of the leather to curl toward the flesh side, and applying suitable pressure to the edge to insure its alinement and uniform curvature.

10. The process of producing a rounded, smooth and finished edge upon leather, which consists in slightly skiving the edge, coating the skived portion with a preparation of cellulose dissolved in volatile hydro-carbon, whereby the treated portion is caused to contract upon drying, and the grain side of the leather to curl toward the flesh side, applying suitable pressure to the edge to insure its alinement and uniform curvature and simultaneously burnishing the curled portion to complete the finished edge.

45 11. The process of producing a rounded,

smooth and finished edge upon leather, which consists in slightly skiving the edge from the flesh side, coating the skived portion with a preparation of cellulose dissolved in a mixture of volatile hydro-carbons of the alcohol group, whereby the treated portion is caused to contract upon drying, and the grain side of the leather to curl toward the flesh side, applying suitable pressure to the edge to insure its alinement and uniform curvature and simultaneously burnishing the curled portion to complete the finished edge.

50 12. The process of producing a rounded, smooth and finished edge upon leather, which consists in slightly skiving the edge, and coating the skived portion with a solution of cellulose and a resinous gum, whereby the treated portion is caused to contract upon drying and the display side of the leather to curl.

60 13. The process of producing a rounded, smooth and finished edge upon leather, which consists in slightly skiving the edge, and coating the skived portion with a preparation of celluloid dissolved in acetone and alcohol, whereby the treated portion is caused to contract upon drying, and the display side of the leather to curl.

70 14. The process of producing a rounded, smooth and finished edge upon leather, which consists in slightly skiving the edge, and coating the skived portion with a dyed preparation of celluloid dissolved in acetone and alcohol, whereby the treated portion is caused to contract upon drying, and the display side of the leather to curl.

In testimony whereof, we have signed our names to this specification, in the presence of two subscribing witnesses.
